UNITED STATES PATENT OFFICE.

HARRY BRIDGMAN SMITH, OF NEW YORK, N. Y., ASSIGNOR TO BRIDGMAN SMITH PATENTS COMPANY, INC., OF BROOKLYN, NEW YORK, A CORPORATION OF NEW YORK.

BOX AND METHOD OF MAKING THE SAME.

Application filed February 2, 1922, Serial No. 533,624. Renewed August 5, 1924.

The present invention is an improvement upon the method and box structure disclosed in my Patent No. 1,408,479, March 7, 1922.

According to that disclosure blank assemblies are produced by what I have described as a continuous method, or in some cases they may be otherwise produced, and these blank assemblies are so formed that when they are folded into box shape and properly secured they present a close approximation in appearance to the highest class of covered boxes, the inner peripheral margins of the shell walls being covered by an overlapped marginal portion of the cover sheet, and all exposed walls and edges of the shell material being concealed by the cover paper, with the exception of certain edges of the shell end wings which are left more or less exposed.

While boxes having the described characteristics are suitable for many purposes, the presence of exposed shell edges renders them undesirable in cases where the highest possible finish is desired. The object of the present invention is to provide modifications and improvements in the above mentioned method and structure, so that boxes otherwise corresponding generally to the previous structure may be produced, but with the important difference that the shell end wing edges as well as all other exposed surfaces and edges of the shell material are overlaid and concealed by the cover blank. The present improvements are also devised so that the boxes may be produced when desired, by a continuous production method generally conforming to the method disclosed in the above identified application, with improvements for the present purposes, as sufficiently described hereafter.

The accompanying drawings show certain exemplifying embodiments of the invention. After considering these persons versed in the art will understand that many modifications may be made within the principles of the invention, and I contemplate the employment of any method of production and structures which are properly within the scope of the appended claims.

In the drawings:—

Fig. 1 is a perspective and largely diagrammatic view, explanatory of the continuous production method.

Fig. 2 is a perspective view of a blank

assembly resulting from operations in accordance with the continuous method or which may otherwise be produced by a separate blank assembly method.

Fig. 3 is a perspective view of the reverse side of the blank assembly.

Fig. 4 shows the assembly with side wings folded up.

Fig. 5 shows the corner laps turned in.

Fig. 6 shows the assembly end wings turned up.

Fig. 7 shows a completed box part.

Fig. 8 is a plan view of one end of a slightly modified blank assembly.

Fig. 9 is a perspective view of a box formed from such an assembly.

Fig. 10 is a plan view of a part of a modified blank assembly.

Fig. 11 is a plan view of another modified assembly.

Fig. 12 is a perspective view of one corner of a box made from an assembly like Fig. 10.

Fig. 13 is a similar view of a box made from an assembly like Fig. 11.

In accordance with the continuous assembly method (Fig. 1) a continuous strip of shell material W, usually card board of suitable grade and thickness, is advanced from a suitable source of supply, such as a roll (not shown) and during its advance at a suitable point is provided with longitudinal creases or score marks 12. At a suitable point in the advance of the shell strip, apertures are punched in it by suitable cutting or punching devices, and this punching may be done in one or two stages as may be convenient, the punching operations, however performed, resulting in the formation of major transverse openings a, of substantially rectangular form. Rectangular enlargements b of these openings are also provided, resulting in the present specific embodiment in a substantially H-shaped opening of which the margins c are usually substantially in line with the longitudinal score marks 12. These apertures define the shape of the shell end wings when the blank assembly is completed.

At a suitable point in the advance of the shell strip it is brought into association with a continuous strip of cover material X which may be advanced from a roll B and is adhesively conditioned on the surface which is to engage the shell material, a glue roll

5 being shown to exemplify means for ap-form by progressive operations. In Fig. 4 applying adhesive to the cover strip. The cover strip is brought in contact with the shell strip and the two are pressed together 5 by suitable means. The cover strip is so proportioned that margins α extend beyond the edges of the shell strip and at a suitable point these margins are folded over and pressed upon the upper (inner) surface of the shell. Desirably at a point beyond the 10 positioning of the cover margins α , as just described, transverse score marks 13 are provided to facilitate subsequent bending. The continuous assembly is then complete, 15 as shown near the left hand portion of Fig. 1. The apertures of the shell leave exposed the adhesively coated cover material, ready for subsequent box forming operations.

Successive portions of the continuous assembly are then severed along the transverse lines 15, producing individual blank assemblies A, Fig. 2. Similar assemblies may be also produced by association of properly formed shell and cover blanks as sufficiently 25 explained in the previously identified application. The individual blank assembly, however produced, in the present representative form, comprises a piece of shell material including a body portion 20, side 30 wings 21, corner laps 23 extending from the ends of the side wings, and end wings 22. The outer or under face of the shell is covered by the cover material which includes portions corresponding generally to 35 the parts of the shell blank above described, and identified by the same reference characters with the addition of a prime mark. Margins α of the cover are turned over and secured to inner marginal portions of the shell along the outer edges of the side wings 40 and corner laps. The shell end wings are so formed that a strip or marginal portion of the cover end wing 22' extends beyond the shell end wing about all of its free sides, 45 and this marginal portion of the cover material is provided with adhesive which may have been applied during the continuous assembly operations as above described, or 50 may be otherwise applied in different assembly methods. The side margins 26 of the shell end wings are located inward considerably from the adjacent edges of the cover end wings, for reasons later described.

At a suitable point in the box formation operations, and in some cases before the individual blank assemblies are severed from the continuous assembly, cuts are made along the lines 24, severing the cover material along lines corresponding to the inner longitudinal lines of the shell corner laps 23. In one way of forming the cuts 24, they may be made at the same time that the transverse severing cuts 15 are made, by a suitably formed cutter or knife.

The assembly is now folded up into box

the combined side wings are folded up and in Fig. 5 the corner laps are turned in, and when the parts are suitably proportioned the inward edges of the corner laps closely 70 abut against each other, although in some cases these ends or edges may be more or less separated. The outer surfaces of the corner laps at a suitable point in the assembly operations are provided with adhesive 75 25, and this application may be made while the blank assembly is still in flat form, as shown in Fig. 3, or at any convenient later stage up to the time of up-folding the assembly end wings.

Fig. 6 shows the assembly end wings folded up against the corner laps, the shell end wings 22 being pressed against the adhesive surfaces 25. The material of the cover end wings 22' extends beyond all the 85 edges of the shell and the outer marginal portions of the cover end wings are pressed against the outer surfaces of the corner laps and firmly secured. The upstanding marginal portions α of the cover end wings are 90 then turned in and adhesively secured to inner end wall surfaces and the box part is then complete as shown in Fig. 7.

The apertures b in the shell material are shown of considerable width in Fig. 1, largely for the sake of clearness of illustration and while, of course, the apertures may be so made, resulting in the edges 26 of the shell end wings being located considerably 100 inward from the side walls of the box, these edges may otherwise be located much nearer the side walls of the box, as shown for example in Fig. 8 where only a narrow space separates these edges from the adjacent longitudinal edges of the corner laps. To correspond with this structure, in the production method as shown in Fig. 1, the apertures b will be made correspondingly narrow. Fig. 9 shows a completed box part made from the blank of Fig. 8, showing 110 that the marginal portions k of the cover end wing material extending beyond the shell edges 26 may be quite narrow, and only sufficiently wide in fact, to provide for proper covering of the shell edges 26 and 115 proper adhesion to outer surfaces of the box end wall. Figs. 8 and 9 also illustrate an arrangement in which the corner laps 23 are relatively short so that their inner ends do not approximately meet, but are in fact, 120 widely separated in the completed box part, as shown in Fig. 9.

In some cases the end edges of the shell end wings may be differently arranged or proportioned. For instance, in Fig. 10 these 125 edges 40 are cut diagonally. When such a blank is folded into box form, as shown in Fig. 12, the shell edges 40 while fully concealed by the cover paper produce an appreciable irregularity or "shoulder" on the 130

exterior surface of the box end and in this way produce an appearance resembling that of one typical form of loose-wrapped box. In some cases the cover material adjacent 5 to the diagonal shell edge 40, for instance, at 45, Fig. 11, may be cut approximately parallel to the shell edge, that is on a diagonal line, leaving, however, a marginal portion 46 of the cover material, sufficient to overlap and cover the shell edge in the completed box, Fig. 13, and also of sufficient width to properly adhere to the outer surface of the adjacent corner lap. This arrangement produces a box still more closely 10 resembling a typical loose-wrapped box.

By the described methods and principles of construction all portions, including the edges of the shell end wings, are fully covered and concealed by overlying portions of 20 the cover material and the box part corresponds to the highest requirements of the covered box trade while being capable of production by rapid and economical methods, generally conforming to the production 25 methods described in the prior application above identified.

The process as herein disclosed may consist only of the production of the complete composite blanks, which may be packed or 30 stored in flat form, in stacks, with great space economy, until it is desired to form them into complete box parts and the blanks may then be fed automatically or by hand to any known or suitable box forming or 35 folding mechanism, with adhesive applied where necessary, to make the completed box parts; or, of course, the folding and securing of the blanks into box form may be done by hand operations where machines 40 are not available.

As sufficiently explained in my prior patents and pending applications, the formation of the central openings *w* in the shell web is in one respect required only for boxes 45 of certain dimensions. Where the dimensions vary so that the end wings and especially the shell portions of the end wings are only as long as the corner laps, the formation of these openings *w* may be omitted; and in that case the shell end wing and corner lap formations will be sufficiently produced by forming the longitudinal openings *b*. The severing cuts along the lines 15 will then sever the corner laps and the shell end 50 wings at the same time. On account of other dimensional variations, the length of the openings *w* may also be varied as desired.

The broader aspects of the production of 60 the cover margins or flaps *k* alongside the longitudinal end wing edges 26, as herein disclosed, are claimed in the present application; but the production of such cover margins or flaps in certain other aspects or 65 more limited aspects, and different varia-

tions of the present method and structure, are disclosed and claimed in my companion applications Ser. No. 612,170, filed January 12, 1923, and Ser. No. 612,171, filed January 12, 1923. 70

What I claim is:—

1. A method of producing covered box blanks comprising advancing a continuous strip of shell material, providing therein at regular intervals generally longitudinal 75 slots of substantial width located substantially inward from the shell edges, applying a continuous strip of cover material to one side of the shell strip, slitting the cover material overlying said slots on lines spaced outward from the inner slot edges to provide free cover margins, and severing the combined materials transversely at substantially mid-length of the slots to produce separate blanks in which said cover margins 80 are available for covering and concealing longitudinal shell end wing edges. 85

2. A method of producing covered boxes comprising advancing a continuous strip of shell material, providing therein at regular 90 intervals generally longitudinal slots of substantial width located substantially inward from the shell edges, applying a continuous strip of cover material to one side of the shell strip, slitting the cover material overlying said slots on lines spaced outward from the inner slot edges to provide free 95 cover margins, severing the combined materials transversely at substantially mid-length of the slots to produce separate 100 blanks in which said cover margins are available for covering and concealing longitudinal shell end wing edges, and folding the individual composite blanks so produced into box form. 105

3. A method of producing covered boxes comprising advancing a continuous strip of shell material, providing regularly spaced central openings of substantial H-form in the shell, applying a continuous strip of cover material to one side of the shell material, turning over and securing marginal portions of the cover material to upper margins of the shell material, severing the cover material on longitudinal lines corresponding 110 to certain of the shell slot portions to effect cover wing separation, severing the combined materials on transverse lines substantially bisecting central portions of the shell apertures, folding the assembly side wings 115 up, turning the corner laps in, turning the combined end wings up against outer surfaces of the corner laps, securing the shell end wings to portions of the corner laps, pressing down extending margins of the 120 cover end wings and securing them to the corner laps to conceal the shell end wing edges, and turning over and securing upwardly extending margins of the cover end 125 wings to inner surfaces of the corner laps. 130

4. A box blank consisting of a piece of shell material and a piece of cover material overlying one side of the shell and having side margins turned over and adhesively secured to margins of the shell, the blank comprising a body portion, side and end wings and corner laps each consisting of portions of the shell and cover material, all of the edges of the shell end wings being located inwardly from the edges of the overlying cover end wing portions, the cover material being longitudinally severed to provide for cover wing separation.
5. A box blank consisting of a piece of shell material and a piece of cover material overlying one side of the shell and having side margins turned over and adhesively secured to margins of the shell, the blank comprising a body portion, side and end wings and corner laps each consisting of portions of the shell and cover material, all of the edges of the shell end wings being located somewhat inwardly from the edges of the overlying cover end wing portions, the cover material being severed substantially along the inner edges of the corner laps.
6. A box part of paper or similar material, comprising a shell and a piece of cover material overlying outer surfaces and exposed edges of the shell, the box end structure including inwardly turned corner laps and end wings lying against outer surfaces of the corner laps, the shell end wing portions having side edges located slightly inward from the side walls of the box, the end wing portions of the cover material having margins extending beyond and concealing side edges of the shell end wings.
7. A box part of paper or similar material comprising a shell and a piece of cover material overlying outer surfaces and exposed edges of the shell, the box end structure including inwardly turned corner laps and end wings lying against outer surfaces of the corner laps, the shell end wing portions having side edges located inward from the side walls of the box, the end wing portions of the cover material having side and end margins extending beyond the side and end edges of the shell end wings, said side margins of the cover overlying and concealing said side shell wing edges and being adhesively secured to outer marginal portions of the corner laps, the end margins of the cover end wings being turned over and adhesively secured to inner margins of the end walls.
8. A paper box consisting of a shell and a cover sheet overlying and concealing all outer surfaces and edges of the shell material, the box end structure being characterized by inturned corner laps, and overlying end wings, said end wings each comprising a shell portion having side edges located slightly inward from the side walls of the box, and cover portions having margins ex-
- tending beyond said side edges of the shell wings and adhesively secured to outer faces of the corner laps.
9. A box blank assembly consisting of a shell blank and an overlying cover blank having margins turned over and secured to inner faces of the shell, the shell comprising a body portion, side and end wings and corner laps, the shell end wings being shorter than the transverse dimension of the body portion, the cover blank having end wings with side margins extending beyond the side edges of the shell end wings.
10. A paper box consisting of a shell and cover material overlying the shell, the box end structure including inturned corner laps, shell end wings shorter than the end width of the box, and cover end wings overlying the shell end wings and having marginal portions concealing the end edges of the shell wings and adhesively secured to outer surfaces of the corner laps.
11. A method of producing substantially flat covered box blanks ready for subsequent folding and securing in box form, each blank including a sheet of relatively stiff body material and a thinner sheet of cover material, comprising producing in the sheet of body material before application of the cover sheet, openings which define edges of end wings spaced substantially away from adjacent edges of the corner laps, applying and securing the cover sheet to the body sheet, and while the composite blank is in substantially flat, unfolded condition, severing the cover material on lines intermediate the adjacent body end wing and corner lap edges and spaced substantially away from the end wing edges, to separate cover end wing and corner lap portions and produce cover margins projecting from the above mentioned body end wing edges, said margins serving to cover and conceal said edges in the set-up box.
12. A method of producing substantially flat covered box blanks ready for subsequent folding and securing in box form, each blank including a generally rectangular cardboard shell and a sheet of suitably dimensioned cover paper, comprising forming in the shell material prior to application of the cover sheet, generally longitudinal openings of moderate width approximately in line with longitudinal fold lines which define the side wings of the completed blank, said openings defining generally longitudinal spaced edges of the shell end wings and corner laps, applying and adhesively securing the cover paper to one face of the shell, advancing the combined materials in a generally linear direction and in substantially flat condition, and while in such condition severing the cover material on generally longitudinal lines intermediate the shell end wings and corner laps and spaced substan-

cially away from the longitudinal shell end wing edges, to produce narrow cover flaps which are adapted to cover and conceal the said shell end wing edges in the set-up box.

13. A method of producing covered box blanks comprising advancing a web of box shell material of substantial thickness, producing at regular intervals in the web, openings which define adjacent substantially separated and generally longitudinal edges of the shell end wings and corner laps, applying and adhesively securing to a face of the shell web a web of sheet cover material which overlies said openings, slitting the cover material while the combined materials are in substantially flat condition, the slits being on generally longitudinal lines at the above mentioned shell openings, said lines being intermediate the confronting shell end wing and corner lap edges and spaced substantially outward from the end wing edges to provide cover margins adapted to conceal said edges in the set-up box, and severing the combined flat webs transversely at regular intervals to produce individual, substantially flat, foldable box blanks of the character described.

14. A method of producing box blanks comprising advancing a continuous shell web of cardboard in a generally lengthwise direction and in substantially flat condition, producing in the web at regular intervals, openings which define adjacent substantially separated and generally longitudinal edges of the shell end wings and corner laps, advancing and adhesively securing to a face of the shell web a continuous web of cover paper

which overlies said openings, slitting the cover paper on generally longitudinal lines at the above mentioned shell openings, said lines being intermediate the confronting shell end wing and corner lap edges and spaced substantially outward from the end wing edges to provide cover margins adapted to conceal said edges in the set-up box, and severing the combined flat webs transversely at regular intervals to produce individual, substantially flat, foldable box blanks of the character described.

15. A substantially flat, composite box blank, suitable for the production of a covered box part by folding and gluing operations, comprising a sheet of cardboard shell material and a sheet of cover paper overlying one surface of the shell and adhesively secured thereto, the blank having at opposite ends central end wings and corner laps extending at each side thereof, said wings and laps each including portions of the shell and cover sheets, the adjacent, generally-longitudinal edges of the shell end wings and corner laps being spaced substantially apart, and the cover paper overlying these spaces being severed in a generally longitudinal direction on lines spaced substantially away from adjacent edges of the shell end wings to provide cover margins which will cover and conceal said edges in the completed box.

Signed at New York city in the county of New York and State of New York this 31st day of January, A. D. 1922.

HARRY BRIDGMAN SMITH.
